UNITED STATES PATENT OFFICE.

ADOLF WIDMER AND FRITZ WIDMER, OF SCHÖNENWERD, SWITZERLAND.

MECHANICAL MOVEMENT.

1,293,278.

Specification of Letters Patent.

Patented Feb. 4, 1919.

Application filed February 5, 1918. Serial No. 215,487.

To all whom it may concern:

Be it known that we, ADOLF WIDMER and FRITZ WIDMER, citizens of the Swiss Confederation, and residing at Schönenwerd, Switzerland, have invented certain new and useful Improvements in Mechanical Movements, of which the following is a specification.

The present invention has reference to improvements in machines for whipping eggs, cream, mayonnaise, dough, and the like, and relates more particularly to a machine of this character in which there is imparted to the whipping member or members a lateral 10 swinging movement as well as an up and down movement, in close imitation of the movements the hand of an operator naturally goes through in beating up such substances.

Our invention will best be understood when described in connection with the accompanying drawings, in which Figure 1 shows a side elevation, and Fig. 2 a front elevation of a preferred form of construction of our improved whipper; Figs. 3 and 4 represent respectively side and front elevations of a modified construction, and Figs. 5-8 show constructional details.

In the construction illustrated by Figs. 1 and 2 the main machine upright 1 journals in its foot portion the one end of the horizontal shaft 2, whose other end is journaled in the floor bearing 1". On this shaft 2 rides idly the pulley 5, and two rigidly connected pulleys 3, 4 are keyed on this shaft and are driven in any suitable manner, by hand, foot, or machine power, preferably by an electromotor. By means of the belt 6 the rotary movement of pulley 3 is transmitted to a pulley 8 fixed on the one end of the shaft 7 which is journaled in the upright 1, parallel to the lower pulley shaft 2. At the other end of this shaft 7 is rigidly secured an eccentric sheave 9 and is surrounded by the strap 10 (Figs. 1, 2 and 8), into whose oppositely disposed sockets 10" are respectively fixed the rods 11, 11'. The former rod 11 is operatively guided in the guide and bearing sleeve 12 which is fulcrumed by means of the laterally extending trunnion 12' (Fig. 7) to a clamp member 14 adjustably secured on the upright 1. A cross-pin, co-operating with a circumferential groove 13' in the trunnion 12', prevents inadvertent loosening of the parts. The upper end of the other rod 11' is pivotally connected to a

lever rod 15, the other end of which is rigidly attached to a rock shaft 16. In the guide-bar arrangement 17, located at the upper end of the upright, reciprocates vertically the slide block 18, which is provided with laterally extending bosses 18' for journaling the shaft 16.

On the shaft 16, close to the lever rod 15, is secured a coupling sleeve 16", in which a shaft 16' is secured in extension of the shaft 16. In order to prevent oil, which is used for lubricating the shaft 16 in the slide block 18, 18', from spreading along the shaft, there is pinned to this shaft 16 the oil guard 18" (Figs. 2 and 5). Helical springs 19 surrounding the guide rods 17' tend to always force the slide block upwardly, for the purpose of counterbalancing the parts and assuring their shockless operation. At the free ends of the shafts 16, 16' are provided supporting members 16" of semicircular cross-section (Figs. 2 and 6) in which the shafts 20' of the whipping members 20 are securely retained by the aid of yokes 24 having each a set screw 24'.

We have shown, by way of example, a cage-like construction of whipping member, but it is obvious that they could also be of any other suitable construction; thus, for instance, they could be provided with helically twisted wire members in place of the straight rods 20" illustrated. On the machine upright is vertically adjustable the double-armed support 23, the outer end sockets 23' of which carry the frames 22 for supporting the bowls 21 in which the stirrers 20 operate.

The described mechanisms impart to the whipping members a two-fold operative movement, one in up and down direction, and another in laterally swinging direction, which, as is well known, is the best complex movement for effectively beating up substances, such as eggs or cream, or the like.

For altering the lateral oscillatory movements of the whipping member within its bowl, the journal sleeve 12, which guides the lower strap rod 11, is shifted relative to the upright, whereby the distance between the eccentric center and the fulcrum for the rod 11 is altered, so that the upper end of the upper strap rod 11', jointed to the lever rod 15, is carried through a respectively larger or smaller radius of rotation.

In the modification illustrated by the Figs. 3 and 4 there is provided a crank mech-

anism in place of the eccentric arrangement above described. The pulley shaft 2' carries the loose pulley 5' and the fixed pulleys 3', 4', and it is vertically adjustable on the upright 1'. By means of the belt 6' the pulley 8' on the shaft 7' is rotated. From the pulley 8' extends outwardly a crank pin 9' to which is operatively secured the crank rod 10' intermediate its extremities, so that a double-armed lever is formed. The lower free end of the longer crank rod arm is guided in the journal sleeve 12', which is pivoted to the machine upright with the possibility of lateral swing movement, as described above in connection with Fig. 7. The upper shorter crank rod arm is articulated to the lever rod 15' fixed to the shaft 16'. The other parts of this modified construction are identical to those above described, with the exception that we have shown here only one bowl 21 and whipping member 20; but we could, obviously, also provide for such double arrangement, without interfering with the general construction and function of the various parts and the inventive principle involved.

What we claim is:—

1. In a mechanism of the class described, the combination of a standard, guides 30 mounted on the standard, a slide mounted in the guides, a rock shaft mounted in the guide, an operated member connected to the rock shaft, an arm extending from the rock shaft, an eccentric mounted on the standard, 35 a lever operated by the eccentric and piv-

otally connected at one end to the arm, and a guide for the opposite end of the lever, and means for rotating the eccentric, whereby the shaft will be simultaneously rocked and reciprocated.

2. In mechanism of the class described, the combination of a standard, a pair of guides supported on the standard, a slide mounted to reciprocate on the pair of guides, buffer springs on the guides below the slide, 45 a rock shaft mounted in the slide, an eccentric mounted on the standard, an operating connection between the eccentric and the rock shaft, an operated element carried by one end of the rock shaft, and means for 50 operating the cam to cause the shaft to reciprocate and rock the shaft and the operated element carried thereby.

3. In mechanism of the class described, the combination of a standard, guides supported thereon, a slide mounted on the guides, an operated element carried at each end of the shaft, means for adjustably mounting the operating elements, an eccentric mounted on the shaft, a lever operated 60 by the eccentric, an arm extending from the shaft and pivotally connected to the upper end of the lever, a pivotally mounted guide for the lower end of the lever, and means 65 for operating the eccentric whereby the operated elements are simultaneously reciprocated and rocked.
